UNITED STATES PATENT OFFICE.

EMIL GOLDSCHMITT, OF BAIREUTH, GERMANY.

LENGTHS-DIVIDING SCALE.

SPECIFICATION forming part of Letters Patent No. 495,219, dated April 11, 1893.

Application filed September 28, 1892. Serial No. 447,131. (No model.) Patented in Germany June 6, 1890, No. 55,912; in France October 15, 1890, No. 208,879, and in England March 12, 1891, No. 4,466.

To all whom it may concern:

Be it known that I, EMIL GOLDSCHMITT, a subject of the King of Bavaria, and a resident of Baireuth, in the Kingdom of Bavaria, Empire of Germany, have invented certain new and useful Improvements in Lengths-Dividing Scales, (for which patents have been obtained in Germany, No. 55,912, dated June 6, 1890; in England, No. 4,466, dated March 12, 1891, and in France, No. 208,879, dated October 15, 1890,) of which the following is a full, clear, and exact specification.

My invention relates to a device for dividing a line of given length into a number of equal parts, and at the same time for reading the length of such divisional parts; another object of my improvements is to determine the height of a triangle, or the length of any perpendicular from a point to a line, without drawing the said perpendicular; and finally my improved scale is provided with an arrangement permitting the measurement of the angle formed by two lines. These improvements are effected by means of two sets of small flat bars, linked one to another in the fashion of lazy-tongs, in combination with a measuring-scale placed in the direction in which the lazy-tongs expand, another measuring-scale placed in a direction perpendicular to the first, and a protractor arranged at the point of intersection of two of the said flat bars, a number of the same being prolonged.

In order to disclose my invention more fully, I will proceed to describe a lengths-dividing scale constructed according to my improvements, reference being had to the accompanying drawing, which is a plan view of the instrument.

The device consists first of a number of small flat bars *e* arranged in two sets, the bars of each set being parallel to one another, and each bar of one set being linked by pins *c* to five bars of the other set. The extensible part formed by the combination of these flat bars is the main part of my lengths-dividing scale. At the ends of this extensible part I provide two legs *A A*, and the four flat bars linked to the same are lettered *d* on the drawing. Only one bar *d* is equal in length to the bars *e*, the other three being shorter as shown.

The legs *A A* are pivotally connected to each other by means of a pin *a*, and may be secured in their relative positions by means of a screw-nut *b*. The lower end of the pin, 55 *a*, [not visible on the drawing] should be pointed, so that it may be pressed into the paper, wood or other material on which the instrument is to be used. Two bars *e* of each set are prolonged, as indicated at *B*, 60 and linked to the legs *A*, in order to insure the rectilinear expansion and contraction of the lazy-tongs. One of the legs *A*, and all bars *e* and *d* parallel to the same, are pointed and numbered in succession 0, 1, 2, 3, 4, &c., 65 the last point bearing the number 16, in the example shown on the drawing. It is of course immaterial of how many bars the instrument is composed, and I preferably construct the same with twenty-one or twenty-six 70 pointed ends, thus permitting the division of a line into twenty or twenty-five parts respectively; but any other number of bars may be employed. It is likewise immaterial whether two bars or more are connected to the legs *A*, 75 and it is obvious that an instrument of larger size than that shown on the drawing may be provided conveniently with a greater number of bars *B*, while the latter may be dispensed with in part or entirely, when the instrument 80 is of smaller size. Finally it is not necessary that each bar *e* of one set should be connected to five bars of the other, though for sake of rigidity of the instrument it is preferable that each bar *e* should be secured at least to three 85 bars of the other set.

To one of the pins *c*—at any place in the extensible part—I secure the measuring-scale *C*, and to the pin *c* distant from the said pin by two bars *e*—or *d*, as the case may be—I 90 likewise secure a frame *f* adapted to receive and to guide the measuring-scale *C*, which by this means is always kept parallel to the line formed by the points of the bars *e*. The scale *C* may be graduated in millimeters and 95 lines. The guide-frame *f* is provided with a wire *h* serving as an index; this wire is placed right over the pin *c* to which the guide-frame *f* is secured. The latter is provided with beveled edges in order to facilitate the reading 100 of the lengths. The graduation of the scale *C* is such as to indicate the distance be-

tween the points of two adjoining bars *e*; that is to say, the divisions of the scale *C* are twice their true length. Of course if the scale *C* and guide-frame *f* are secured to pins *c* distant from each other by three bars *e*, the divisions of the scale *C* will be three times their true length, and I may fix the guide-frame *f* at any distance from the fixed end of the scale *C*, without departing from the nature of my invention. Along the inner beveled edges of the guide-frame *f* I arrange two verniers *D* and *D'* respectively, one permitting to read tenths of a millimeter, and the other half points.

15 To one of the pins *c*—preferably one of the horizontal row nearest the points of the bars *e*—I secure a second measuring-scale *C'* and guide the same in a guide-frame *f'* fixed to another pin *c*, so that the direction of the scale *C'* is always perpendicular to that of the scale *C* and to the line formed by the points of the bars *e*. The construction of the scale *C'* and guide-frame *f'* is substantially the same as that of the scale *C* and guide-frame *f*, and 20 I may also provide verniers *D'' D''* for the measuring-scale *C'*. The graduation of the latter is such that the wire *h'* serving as an index indicates the length of the perpendicular from the center of the pin *a* to line formed 25 by the points of the bars *e*. I have added the verniers *D D' D'' D''* merely for insuring a more exact reading of the lengths, and when such exactitude is not needed, the said verniers may of course be dispensed with.

30 At the point of intersection of two bars *B* (or it may be at the joint of the legs *A*) I secure the protractor *E* to one of the same, and to the other a piece *g* of wood, metal or other suitable material, and I form a beveled edge 35 to the said piece *g* so that it may serve as a pointer and indicate on the protractor *E* the angle formed by the bars *B*, or the legs *A*. I may also provide a vernier for securing 40 more exact indications than by the protractor *E* alone.

45 I will now describe the operation of my improved lengths-dividing scale, first for dividing a line into a given number of parts and for ascertaining the length of the divisional part and of the entire line; secondly for determining the length of a perpendicular from a given point to a given line; and thirdly, for measuring the angle formed by two given lines.

50 First example: I will suppose that a line is to be divided into nine equal parts. The point of the leg *A* bearing the indication 0 is then placed at one extremity of the said line, and the lazy-tongs extended until the point bearing the indication 9 coincides with the other end. When the material on which the line to be divided is soft, the division may simply be effected by pressing the points 1 to 8 into the material. Or the divisional 55 strokes may be marked with a pencil or scriber. Now, in order to ascertain the length of the divisional part, the measuring-scale *C*

and its verniers *D* and *D'* are consulted, and the length indicated on the same by the wire *h* may for instance be found equal to sixteen and ⁷⁰ nine-tenths millimeters, or eight lines. In order to determine the length of the entire line, it is but necessary to multiply this indication by nine, thus the length of the line would in this example be equal to one hundred and ⁷⁵ fifty-two and one tenth millimeters, or six inches. It will be found very convenient to affix a suitable table of multiplication to the instrument.

Second example: The length of the perpendicular from a point to a line is to be ascertained. The point of the pin *a*, at the intersection of the legs *A*, is driven into the paper, wood, &c., at the indicated point and the lazy-tongs drawn apart until the numbered points ⁸⁵ of the bars *e* come to lie all on the given line. The length of the perpendicular will then be indicated by the wire *h'* on the measuring-scale *C'* and its verniers *D'' D''*. It will be seen that it is not necessary the perpendicular ⁹⁰ should be drawn.

Third example: To measure the angle formed by two given lines. It is immaterial whether the lines extend to the summit of the angle or not. The bars *B* to which the protractor *E* ⁹⁵ and the pointer *g* are fixed, are placed so that their edges coincide with the given lines, when the angle formed by the latter will be indicated on the protractor *E* by the pointer *g*.

The instrument may also be used for enlarging or reducing lengths in a great many ratios and much more simply than was possible heretofore.

The above described form of construction, consisting in securing the lazy-tongs between ¹⁰⁵ legs *A*, is the form in which I prefer to make my invention; but the extensible part may also be employed without the use of legs *A*, when of course the measuring-scale *C'* becomes of no use. The instrument would then ¹¹⁰ be reduced to its simplest form and consist only of the lazy-tongs, of the measuring scale *C* arranged in the direction in which the expansion and contraction take place, and of the guide-frame *f* with its indicating wire *h*. ¹¹⁵ This form of construction would only permit of dividing a line into equal parts, and to determine the length of the parts and of the entire line, in the manner described above.

I will also mention that the employment of ¹²⁰ my lengths-dividing scale is not limited to the division of lines on plane surfaces, but the same may also be used for dividing lines on curved surfaces, as the instrument may be made of material permitting of being bent.

I am aware that lazy-tongs have been employed in lengths-dividing-scales, but the graduated measuring-scale was placed transversely to the lazy-tongs; now, as the extension of the latter in length is not proportionate to that in breadth, it would have been necessary to provide a disproportional graduation on the measuring-scale, and this would have increased the cost of manufacturing the ¹³⁰

instrument. In this respect my invention is a valuable improvement over the old length-dividers. Another advantage of my construction, not to be found in the similar instruments used hitherto, is that the rectilinearity of the extensible part formed by the lazy-tongs is insured by connecting each bar *e* of one set to three bars at least of the other set.

Having thus fully described the nature of my invention, what I desire to secure by Letters Patent of the United States is—

1. In a lengths-dividing-scale, the combination with the legs *A*, *A*, pivoted together at one end, and the bars *d*, and *e*, connected together and to the legs *A*, *A*, in the manner of lazy-tongs and adapted to be extended as described, of a measuring scale *C* arranged in the direction in which the extension of the lazy-tongs is effected, for the purpose specified.

2. In a lengths-dividing-scale, the combination, with the lazy-tongs formed by the bars *d* *e*, of the legs *A*, bars *B*, the measuring-scale *C* and guide-frame *f*, provided with index *h*, substantially as and for the purpose described.

3. In a lengths-dividing scale, the combination, with the lazy-tongs formed by the bars *d* *e*, of the legs *A*, bars *B*, the measuring-scale

C, guide-frame *f* provided with index *h*, and with verniers *D* *D'*, substantially as and for the purpose described.

4. In a lengths-dividing-scale, the combination, with the lazy-tongs formed by the bars *d* *e*, of the legs *A*, bars *B*, the measuring-scale *C*, guide-frame *f*, provided with index *h*, and with verniers *D* *D'*, the measuring-scale *C'* and guide-frame *f'*, provided with index *h'* and with verniers *D*² *D*³, substantially as and for the purpose described.

5. In a lengths-dividing-scale, the combination, with the lazy-tongs formed by the bars *d* *e*, of the legs *A*, bars *B*, the measuring-scale *C*, guide-frame *f* provided with index *h*, and with verniers *D* *D'*, the measuring-scale *C'*, guide-frame *f'*, provided with the index *h'* and with verniers *D*² *D*³, and of the protractor *E*, provided with pointer *g*, substantially as and for the purpose described.

In testimony whereof I have signed this specification in the presence of two subscribing witnesses.

EMIL GOLDSCHMITT.
